US0D1109732S

(12) **United States Design Patent** (10) **Patent No.:** **US D1,109,732 S**
(45) **Date of Patent:** **** Jan. 20, 2026**

(54) **SMART RING WITH DISPLAY SCREEN**

(71) Applicant: **MO YOUNG LIMITED**, Shenzhen (CN)

(72) Inventors: **Ziyan Chen**, Shenzhen (CN); **Wuxian Wang**, Shenzhen (CN)

(73) Assignee: **MO YOUNG LIMITED**, Shenzhen (CN)

(**) Term: **15 Years**

(21) Appl. No.: **29/990,821**

(22) Filed: **Feb. 25, 2025**

(30) **Foreign Application Priority Data**

Jan. 23, 2025 (CN) 202530047550.8
